UNITED STATES PATENT OFFICE

144,396

DESIGN FOR A COMBINED SWIM AND PLAY SUIT

Margit Fellegi Laszlo, Los Angeles, Calif., assignor to Cole of California Inc., Los Angeles, Calif., a corporation of California

Application August 24, 1945, Serial No. 121,623

Term of patent 3½ years

(Cl. D3—17)

To all whom it may concern:

Be it known that I, Margit Fellegi Laszlo, a citizen of the United States of America, residing at Los Angeles, in the county of Los Angeles and State of California, have invented a new, original, and ornamental Design for Combined Swim and Play Suit, of which the following is a specification, reference being had to the accompanying drawing, forming a part thereof.

The figures in the drawing are: Figure 1 is a front perspective view of a combined swim and play suit and Figure 2 is a rear perspective view thereof, showing my new design.

I claim:

The ornamental design for a combined swim and play suit, as shown.

MARGIT FELLEGI LASZLO.
